UNITED STATES PATENT OFFICE.

SAMUEL E. KAYLER, OF ALLIANCE, OHIO.

METHOD OF STRIPING DUCO AND THE LIKE.

No Drawing.

Application filed September 26, 1925. Serial No. 58,751.

To all whom it may concern:

Be it known that I, SAMUEL E. KAYLER, a citizen of the United States, residing at Alliance, in the county of Stark and State 5 of Ohio, have invented a certain new and useful Method of Striping Duco and the like, of which the following is a specification.

This invention relates to a method of 10 striping lacquers such as "duco" which is the trade name of a feroxiline material composed of nitrated cotton and various acetates, and used extensively for coating the body, fenders and other sheet metal portions of automobiles.

This "duco" is usually sprayed upon the automobile as owing to its very rapid drying qualities a brush cannot be successfully used in applying the same.

20 It is customary in finishing automobile bodies, fenders and the like to stripe certain portions of the same with a different color for decorative purposes. With this "duco" it has been found practically impossible to 25 paint a stripe of "duco" upon a body coating of "duco", because the stripe when applied with a brush softens or dissolves the body coat, causing the striping to run and merge with the body coat.

30 For this reason it is customary to stripe a body coat of "duco", with an ordinary paint or enamel of a different color, but since paints or enamels do not have the wearing or elastic qualities of "duco", the 35 striping soon wears off in places detracting from the appearance of the automobile.

The object of the present invention is to provide means for easily and accurately applying a stripe of one color of "duco" upon 40 a body coat of a different color of "duco", without permitting the same to soften or merge with the body coat, thus overcoming the difficulty experienced by endeavoring to paint a stripe of "duco" upon a body coating of "duco" and avoiding the objections 45 to painting with common paint or enamel upon a body coating of "duco".

In carrying out the invention the body of 50 the automobile or other object may be coated with "duco" of any desired color in the

usual manner. "Duco" of any other desired color is then applied to the body coat in stripes at the places desired by means of a ruling pen.

An ordinary two-tine ruling pen such as 55 is commonly used by draftsmen, is best adapted for carrying out the striping operation, the "duco" of the color to be used for striping being placed between the tines of the pen in the usual manner, and the pen 60 drawn across the surface of the body coat inking of "duco".

The tines of the pen just cut into the body coating sufficiently to form two parallel grooves or scores in the body coat of "duco", 65 the striping coat of "duco" flowing from the pen and filling the narrow space between said grooves or scores which prevent the striping coat from overrunning and merging with the body coat, producing a 70 sharp clean cut stripe of the color of "duco" upon the body coating of "duco".

This method has been used extensively by applicant in applying stripes of one color of "duco" upon a body coating of a different 75 color of "duco" and it has been found by experience that a person with very little training can quickly and neatly apply stripes of "duco" in this manner.

I claim:

1. The method of striping "duco" and the like which consists in applying a stripe of one color of "duco" upon a body coat of another color of "duco" by means of a ruling pen.

2. The method of striping "duco" and the like which consists in applying a stripe of one color of "duco" upon a body coat of another color of "duco" by means of a two-tine ruling pen.

3. The method of striping "duco" and the like which consists in forming parallel spaced scores or grooves in a body coat of "duco" and flowing "duco" of another color upon the body coat between said scores and 95 grooves.

In testimony that I claim the above, I have hereunto subscribed my name.

SAMUEL E. KAYLER.
